UNITED STATES PATENT OFFICE.

CHARLES F. RANDALL, OF CHICAGO, ILLINOIS.

DUMPING DEVICE.

1,392,448.

Specification of Letters Patent.

Patented Oct. 4, 1921.

Application filed September 20, 1919. Serial No. 325,163.

To all whom it may concern:

Be it known that I, CHARLES F. RANDALL, a citizen of the Dominion of Canada, residing at Chicago, in the county of Cook and 5 State of Illinois, have invented certain new and useful Improvements in Dumping Devices, of which the following is a specification.

This invention relates to dumping devices.

It is particularly applicable to dumping vehicles, such as trucks and the like.

An object of the invention is to provide an improved dumping device.

Another object is to provide a dumping device which may be readily applied to ordinary vehicles.

Another object is to provide a dumping device with a body from which material 20 may be readily dumped.

Another object is to provide a dumping device having a body with a material retaining obstruction which is automatically removed when the body is in dumping position.

Another object is to provide a dumping device readily adapted for spreading material.

Another object is to provide a dumping device having a body also adapted for general service.

Another object is to provide a dumping device which is simple, reliable and easily operable.

Other objects and advantages will appear from the specification and claims.

An embodiment of the invention, applied to a motor truck, is illustrated in the accompanying drawings, in which—

Figure 1 is a side elevation of the device in carrying position.

Fig. 2 is a side elevation thereof in dumping position.

Fig. 3 is a section on line 3—3 of Fig. 1.

Fig. 4 is a section on line 4—4 of Fig. 1.

Fig. 5 is a perspective of the underframe, showing the latches for holding the body in carrying and dumping positions, and

Fig. 6 is a section on the line 6—6 of

Fig. 4.

The dumping device has a body 5 for holding the material to be transported. The body is, in general, of the usual type and is adapted to be carried upon the chassis 55 frame of an ordinary vehicle, such, for example, as a motor truck. The body is pri-

marily supported in carrying position upon a pair of forward rollers 6 and a pair of rear rollers 7. The body is provided on each side of the bottom with an angle iron 60 8. The horizontal flanges of these angle irons form tracks for rollers 6 and 7.

Rollers 7 are carried by a shaft 9 journaled in bearings 10, and rollers 6 are similarly carried by a shaft 11 journaled in 65 bearings 12.

The bearings for shafts 9 and 11 are mounted upon a frame work which may be secured to some part of the chassis of the vehicle, such as the channel bars 13 found in the ordinary motor truck. The

frame work comprises a pair of angle irons 14, extending along the top of and secured to channel bars 13 by suitable means such as the clamps 15 and 16, a pair of longitudinally extending plates 17, and suitable 70 75 strengthening cross pieces.

Supported upon and rigidly secured to plates 17 are a pair of racks 20, which extend rearwardly from the front of body 5 when the body is in carrying position. Each 80 rack is engaged by a pinion 21 rigidly secured to a shaft 22. Shaft 22 also has journaled thereto a pair of rollers 23.

The rollers 23 are positioned between the angle irons 14 and a coöperating pair of 85 angle irons 24. Angle irons 14 and 24 are spaced apart and secured together at their rear ends by angle posts 25 and 26 and inter-connecting angle irons 27 and 28. At

their forward ends irons 14 and 24 are 90 spaced apart and secured together by a pair of angle posts 30 and 31 and interconnecting angle irons 32 and 33. The horizontal flanges of angle irons 14 and 24 thus provide a double track for each of the rollers 23

to position shaft 22 and maintain pinions 95 21 in engagement with rack 20. Shaft 22 is extended at each end beyond the line of the body for the application of a suitable crank

33 for turning the shaft and the pinions 100 carried thereby.

When shaft 22 is turned by the crank the pinions travel along their respective racks and slide and tilt body 5 to dumping position or carrying position, as will be herein-after described.

A pair of levers 35, one on each side of the body, are each pivotally carried at one end by shaft 22 and at the other end are secured to some part of body 5 by suitable pivots 36. Levers 35 are braced and interconnected by 110 a brace 37 which insures their operating to-

gether. A pair of stops 38, in the form of U-shaped straps or yokes of angle iron, are secured to the bottom of body 5. The opposite ends of shaft 9 project beyond these 5 yokes between the end walls thereof, as most clearly shown in Figs. 1, 2 and 4.

When body 5 is in carrying position the rear vertical wall of yokes 38 may engage shaft 9 to limit the forward movement of 10 the body. It is not necessary, however, that the forward movement of the body be limited by the yokes. As the body is moved rearwardly, due to the action of crank 33, racks 20, pinions 21 and levers 35, the yokes also 15 move rearwardly, the forward vertical walls thereof finally engaging shaft 9. The sliding movement of the body is thus arrested. Further rotation of crank 33 thereupon begins to elevate the forward end of the body, 20 shaft 9 and rollers 7 acting as pivots, as shown in Fig. 2. The body is thus first slid rearwardly and then tilted to dumping position. The body is prevented from being thrown or jarred from its proper position by 25 the opposing forces of rollers 7 against the bottom and shaft 9 against yokes 38.

Reverse rotation of crank 33 first tilts the body back to its horizontal position and then slides the same forwardly upon rollers 7 30 and 6 to the carrying position shown in Fig. 1.

Body 5 is retained in carrying position by a manually released holding device or latch. This device comprises a catch 40 35 adapted to engage and hold shaft 22. Catch 40 is carried by a rod 41 which is journaled in the end posts 30 and 31 and a central bracket 42 carried by angle iron 32. Bracket 42 is bifurcated, as shown in Figs. 3 and 5, 40 catch 40 being located between the bifurcations. Rod 41 has both its ends extending beyond end posts 30 and 31 and bent at right angles to form a handle 43 on each side. Bracket 42 is provided with a ledge between 45 its bifurcations to engage the under side of catch 40 and prevent the same from rotating too far when shaft 22 is not in a position to be engaged and held thereby. To facilitate the positioning of rod 42 and allow the 50 handles to be formed before assembly, the rod may be made in two sections, joined by a suitable coupling 45.

As the body is moved to carrying position, shaft 22 strikes the forward cam surface of 55 catch 40 and raises the catch. When shaft 22 passes the hook of the catch, the catch drops back, holding the body in carrying position.

In this condition the body can not slip 60 backward and crank 33 and pinions 21 are locked against rotation. This prevents the accidental displacement of the body from jars or shifting loads or the premature dumping of the same by inadvertent operation of crank 33.

The body of the dumping device is closed at its rear end by a movable tail-gate 50. The tail-gate is provided near its top with a pivot retaining-rod 51. The ends of rod 51 project beyond the body on each side where 70 they are adapted to be held in the position shown by the full lines of Figs. 1 and 2, by a pair of hooked retaining members 52 slidably carried by the body in brackets 53. The tail-gate is also provided on opposite sides 75 near the bottom with a pivot retaining-rod 54, which is held to the tail-gate by a pair of straps 55. The ends of rod 54 also project beyond the body, on each side, where they may be engaged and held by pivoted catches 80 56. Each catch is pivoted to the body by a bracket 57 and has its forward end inclined and provided with an elongated opening 58. Within these openings are pins or stud bolts 60 which connect the catches with a pair of 85 slideable trip bars 61, one on each side of body 5.

When the tail-gate is in closed position at the bottom, as shown in Fig. 1, the hooks of catches 56 overlie the ends of rod 54 and 90 the bottom of the tail-gate is pivotally retained.

Each trip bar 61 is provided with a pivotal latch 62, which, when the body is in carrying position, drops behind a stop 63, attached 95 to the body. The bottom of the tail-gate is thus held closed until automatically tripped when the body is moved to dumping position, as will be hereinafter described.

To insure that catches 56 properly overlie 100 rod 54, to securely lock the bottom of the tail-gate when it returns, upon the return of the body to carrying position, each of the levers 35 is provided with a latch actuating cam 64. Cams 64 are in a position to be 105 engaged by outwardly extending projections 65 of the trip bars 61. When the body is tilted from dumping to horizontal position, and upon the forward movement of the body and levers 35 to carrying position, cams 64 110 and projections 65 come into operative engagement and trip bars 61 are moved in a forward direction. The forward movement of trip bars 61, through the action of pins 60 and inclined slots 58, causes latches 56 to be 115 positively moved about their pivots to locking position over the ends of rod 54.

The bottom tail-gate latches 56 are operated to release the bottom of the tail-gate when the body is tilted to dumping position, 120 by levers 35 acting upon latches 62. The levers first engage the tails of their respective latches and raise the forward ends of the latches out of engagement with stops 63. This unlocks the trip bars 61 and further 125 movement of the body and levers 35 acts through the pivots of latches 62, to move the trip bars rearwardly. This movement of the trip bars, through the coöperation of pins 60 and inclined slots 58, raise the lock- 130

ing ends of catches 56 and the bottom of the tail-gate is released. By automatically releasing the tail-gate only, after the body has been tilted to substantially its full dumping 5 position the weight of the load in the rear of the body is maintained, and this load, being back of the pivot about which the body tilts aids in the tilting operation.

In order to facilitate the spreading of the 10 material dumped from the body, the open position of the tail-gate may be limited to give the proper spread by adjustable stops 70. Stops 70, of which there may be one on each side, are mounted on the rear of the 15 side walls of the body by removable pins 71. When a full opening of the tail board is desired, stops 70 are moved to the full line position shown in Figs. 1 and 2. If, however, the opening of the tail board is to be limited, 20 stops 70 are moved to the dotted line position of Fig. 2, where they may be engaged by the ends of a bar 72 which is secured to the tail-gate by straps 55. The opening of the tail-gate may be limited to the desired 25 amount by inserting pins 71 through the proper openings 73 in stops 70.

When the material carried by the body is being dumped, particularly if it is being spread slowly, the load in the forward end 30 of the body may remain, although the load at the rear is considerably reduced. This unbalance of the load causes considerable back pressure in levers 35, tending to rotate pinions 22 in the reverse direction and allow 35 the body to return to horizontal position. Such premature return movement is prevented by automatically locking the body in its tilted position.

The body is locked in its tilted position by 40 a latch or catch 75, which engages and holds shaft 22 in its rearmost position. Hooked catch 75 is secured to a rod 76 which is pivotally carried by a bracket 77, secured to the angle cross bar 28. Rod 76 is made in two 45 pieces, held together by a coupling 78 and has its outer ends bent at an angle to form handles 79. These handles are within easy reach of the operator from the side of the vehicle. As shaft 22 and its pinion 21 are 50 moved rearwardly to tilt the body to dumping position shaft 22 contacting with the lower cam surface of the hooks of catches 75, raises the catches and passes beyond the same. When the shaft passes beyond the 55 hooks of the catches, the catches drop and the body is locked in tilted position until shaft 22 is released by the raising of catches 75, through the action of the operator turning one of the handles 79. When the catches 60 are raised, the reverse rotation of crank 33 will return the body to carrying position.

When it is desired to use the body for transporting merchandise or materials which cannot or should not be dumped, the tail-gate 65 may be swung outwardly at the top to pro-

vide additional carrying space. To accomplish this duplex movement of the tailgate, retaining members 52 are raised above the ends of rod 51. The top of the tail-gate is thus released and may be swung outwardly 70 about rod 54 as a pivot to the dotted line position of Fig. 1. The extent of this movement is controlled and the top of the tailgate is held by chains 80, secured at one end to rod 51 and at any other desired point 75 throughout their length by hooks 81, which pass through or between the links to anchor the chain to the body.

In order to insure the proper centering 80 of the body when it returns from tilted position and to prevent jars or shifting loads from shifting the body from its proper central position the bottom of brace 37 is provided with a pair of centering members 82. These members have inclined downward projections 85 adapted to engage the upper outer corners of the underframe. The inclined surfaces of these projections engaging the corners of the under frame insure the proper centering of the body when it is tilted back 90 to horizontal position and provide oppositely directed wedging actions which firmly retain the body in central position.

Having described my invention, what I 95 claim is:—

1. A dumping device having in combination, a body with a pivoted tail-gate, a roller supporting said body, a rack and pinion, a lever connected to the axis of said pinion and pivotally secured to said body 100 for sliding and tilting said body upon said roller, a latch for holding said tail-gate in closed position, and means operated by said lever for releasing said latch when said body has been tilted.

2. A dumping wagon having a chassis frame and a body mounted thereon arranged to be moved into dumping position in combination with a pair of rollers connected to opposite ends of a transversely positioned 110 shaft mounted in fixed bearings on the chassis, near the longitudinal median portion of the body when the latter is on the chassis; another pair of rollers mounted on a similar shaft near the rear portion of the 115 body, the ends of the rear shaft extending beyond the rollers; an elongated stirrup fixed to each side of the body inclosing the extended ends of the rear shaft and serving as stops when the body is dumped; a pair 120 of racks fixed to the chassis extending rearwardly from the front end thereof; a pair of pinions, one for each rack; a transversely extending shaft carrying the pinions; a pair of bars pivotally connecting said shaft to 125 the body; a crank to rotate the pinions and a pair of bars parallel with the racks to maintain the pinions in mesh with the racks.

3. A dumping wagon having a body and 130

a chassis in combination with two pairs of rollers upon which the body normally rests, one pair being located near the rear end and on the shaft of which the bed pivots when being dumped; a rack extending rearwardly from the front end of the chassis; a transversely extending shaft connected to the body by a link; a pinion on said shaft meshing with the rack; a handle to rotate the pinion; a guard bar parallel with the rack and spaced above the shaft; an automatically engaging latch mounted on the chassis arranged to hold the front end of the body down and to prevent its rearward movement on the rollers by its engagement with said shaft and another transversely extending shaft to release the latch.

4. A dumping wagon having a body and a chassis in combination with two pairs of rollers mounted on the chassis upon which the body normally rests, one pair being located near the rear end and on the shaft of

which the body pivots when being dumped; a pair of racks extending rearwardly from the front end of the chassis and fixed thereto; a transversely extending shaft; a pair of pinions on the shaft in mesh with the respective racks and movable along the racks; a pair of guard bars parallel with the respective racks and spaced above the shaft; a pair of links pivoted to said shaft near each end thereof and to each side of the body respectively; an automatically operatable latch near the front ends of the racks engaging the pinion shaft to hold the body down and to prevent its rearward movement; another similar latch near the rear ends of the racks automatically to engage said pinion shaft to lock the body in dumped positions, and transversely extending shafts, one for each latch, to open the respective latch.

In testimony whereof I hereunto subscribe my name.

CHARLES F. RANDALL.
